ADJUSTABLE STORAGE RACK AND BEAM CONSTRUCTIONS THEREFOR

John C. Kimpton, Livonia, Mich., assignor to Palmer-Shile Company, Detroit, Mich., a corporation of Michigan

Filed Oct. 9, 1962, Ser. No. 229,385
11 Claims. (Cl. 211—177)

This invention relates to adjustable storage racks and beam constructions therefor. More particularly, the present invention relates to improved adjustable storage racks which may be assembled to accommodate various types of material to be stored in stacked condition, and the configuration of rail or beam members used in such racks.

It is an object of the invention to provide an improved adjustable storage rack which greatly reduces both manufacturing and shipping costs for a rack of specified capacity, and permits increased capacity in a rack fabricated with a specified amount of metal.

It is another object of the invention to provide an improved adjustable storage rack construction in which, for a specified capacity, beam members of less cross-sectional height may be used, thus decreasing the total necessary height for each storage level and in some cases permitting the addition of an extra storage level in each rack section.

It is a further object of the invention to provide an improved beam member construction which has increased resistance to deflective and torsional forces, and which is also useful in racks used for storing different types of merchandise requiring identification.

It is also an object of the present invention to provide an improved beam member construction for storage racks which increases manufacturing economy.

Other objects, features, and advantages of the present invention will become apparent from the following description, the appended claims and the accompanying drawings, in which:

FIGURE 1 is a side elevational view of several sections of the novel storage rack embodying the present invention and showing the same in assembled relationship;

FIG. 2 is a top plan view of one section of the rack illustrated in FIG. 1 taken in the direction of the arrows 2—2 and illustrating the relative length and width of a typical section;

FIG. 3 is an enlarged end elevational view of the structure illustrated in FIG. 1;

FIG. 4 is an enlarged side elevational view of one of the beam members illustrated in FIG. 1;

FIG. 5 is a top plan view of the beam member shown in FIG. 4;

FIG. 6 is a cross-sectional view taken along the line 6—6 of FIG. 4 and showing the cross-sectional configuration of the beam member;

FIG. 7 is an enlarged cross-sectional view of the beam member illustrating the dimensional ratio ranges of beam members embodying the invention; and

FIGS. 8A and 8B set forth tabulations of test results which facilitate a comparison of conventional channel section beams with beams embodying the present invention.

The illustrated embodiment of the invention comprises an adjustable storage rack having a plurality of vertical

2

end units of identical shape and a plurality of horizontal beam members, the latter being provided in the desired number and lengths as required for the particular installation. The end units each have front and rear posts connected by cross members and are adapted to be placed in horizontally spaced relationship in accordance with the lengths of the beam members, the various components of the end units preferably being formed of steel or other structural materials having sufficient strength to withstand the forces exerted thereon. The ends of the beam members have connecting means for attachment to the front and rear posts at any of various desired levels, the vertical spacing of the beam members being chosen in accordance with storage requirements.

10 The beam portion of each beam member may be formed from flat or sheet steel, or other suitable structural material having a substantially constant thickness, and has a novel cross-sectional configuration. This configuration comprises upper and lower horizontal flange

20 portions, a vertical web portion between and spaced from the flange portions and disposed between imaginary vertical planes connecting the edges of the flange portions, and two inclined web portions, one connecting the upper edge of the vertical web portion with one edge of the upper flange portion, and the other connecting the lower edge of the vertical web portion with one edge of the lower flange

25 portion. Preferably, the horizontal distance between a flange portion edge connected to the vertical web portion and an imaginary extension of the vertical web portion is

30 between 40% and 65% of the total beam width. The height of the vertical web portion is preferably between 20% and 60% of the total beam height. The total width of the beam is between 25% and 65% of the total beam height.

35 Referring more particularly to the drawings, a storage rack embodying the present invention is generally indicated at 11 and comprises a plurality of end units generally indicated at 12, and beam members generally indicated at 13. Each end unit 12 comprises front and rear generally channel sectioned posts 14 and 15 with cross braces

40 16 and diagonal braces 17 connecting the posts 14 and 15 to form a rigid unit. The height of the posts 14 and 15 is such that each end unit 12 may fit within the vertical confines of a warehouse or other storage area. The posts

45 14 and 15 are provided with vertically spaced slotted portions 18 pressed outwardly from the web portions of the posts without removing material therefrom for mounting a plurality of beam members 13 at the desired height, as shown in FIGURE 1.

50 Each beam member 13 comprises an elongated member having a novel cross-sectional configuration, described hereinafter in greater detail, and connecting members 19 and 21 secured to opposite ends thereof, as shown in FIG. 4. Each connecting member is of generally L-

55 shaped cross section, as shown in FIG. 5, having one flange secured to the end of the beam 13. The other flange of each connecting member has a plurality of downwardly extending post-engaging teeth 22, as shown in FIG. 4.

60 The connecting members 19 and 21 are of opposite hands, as shown in FIG. 5, and are adapted to interlock with the posts 14 and 15 in a manner described in detail in United States Patent No. 3,044,633, issued July 17, 1962, to E. A. Baker, Jr. and assigned to the

assignee of the present invention. When so assembled, the storage rack 11 may be formed in adjacent sections as shown in FIGURE 1, the sections being interconnected in that each post 14 or 15 may receive connecting members 19 and 21 of the beam members 13 extending in both directions therefrom. When so assembled, the beam members are rigidly interlocked with the end units due to the engagement of the teeth 22 in the slots 18 which hold the connecting members against the posts. The heights of the beam members 13 in each section of storage rack 11 may be chosen to suit individual requirements, that is, in accordance with the height of the material or merchandise to be stored on the rack.

As shown in FIG. 2, no front-to-rear interconnecting means are normally provided between the beam members 13 secured to the front and rear posts 14 and 15, except the interconnecting means provided by the end units 12. This facilitates quick assembly and disassembly of the storage racks, but places a requirement on the beam members that they be of sufficient strength to withstand the applied bearing loads without front-to-rear lateral support at intermediate portions of the beams. The required beam lengths may be quite substantial with respect to the depth of end units 12, as shown in FIG. 2. Ordinarily, pallets or the like will be placed on each pair of front and rear beam members 13, and the pallets will be distributed along the entire length of the beam members 13, with the result that the bending and torsional loads on the beam members are quite severe. It may also be observed (see FIGURE 1) that as the height of each beam member cross section increases, the free space available for storage between the beam members decreases.

In accordance with the present invention, each beam member 13 is provided with a novel cross-sectional configuration which is of special advantage in combination with the other components of the storage rack 11.

The construction of each beam member 13 is shown in detail in FIG. 7. Each beam member is preferably formed of flat or sheet steel stock having a substantially constant thickness. Each beam member 13 has an upper horizontal flange portion 23, a lower horizontal flange portion 24, a vertical web portion 25, an upper inclined web portion 26 and a lower inclined web portion 27, these portions being faired into each other by curved connecting radii portions.

The flange portions 23 and 24 are in vertically spaced relationship, being contained between imaginary vertical planes, indicated at 28 and 29. In the embodiment of the invention illustrated, the vertical web portion 25 is shown as equidistantly spaced from the flange portions 23 and 24. The upper inclined web portion 26 connects the upper edge of the vertical web portion 25 with one edge of the upper flange portion 23 while the lower inclined web portion 27 connects the lower edge of the vertical web portion 25 with one edge of the lower flange portion 24. In the illustrated embodiment, the web portions 26 and 27 are connected to the edges of the flange portion 23 and 24, respectively, which lie in the vertical plane 28. The horizontal distance A between plane 28 and an imaginary extension of the web portion 25 is between 40% and 65% of the total width F of the beam 13. The height B of the web portion 25 is between 20% and 60% of the total height D of the beam 13. The total width F of the beam 13 is preferably between 25% and 65% of its total height D.

A beam having the above-described construction has been found to exhibit substantially improved load-carrying characteristics when subjected to loads of the type normally encountered in a storage rack 11. Beams having cross-sectional configurations not conforming to the above description, but fabricated of the same stock and having the same amount of metal, were found to have markedly less resistance to deflection and twisting forces. For specified capacity requirements, substantially less metal and a lesser total height D have been found necessary

when using the novel beam configuration as compared with conventional shapes.

As an example, for a conventional channel section beam member of the cross-sectional shape shown in FIG. 8A having a span or total length of 106 inches and a rated or safe capacity of 5800 pounds per pair of beams, the following dimensions and other characteristics were found necessary:

Span: 106 inches.
10 Rated capacity per pair: 5800 lbs.
Section: 5 inches (height) x 3 inches (width) x No. 7 gauge.
15 Blank size: 10 $\frac{1}{16}$ inches x 106 inches x No. 7 gauge.
Weight per beam: 56.9 lbs.
Maximum twist at rated load: 6.5°.
Maximum deflection at rated load: 0.301 inch.

A beam of 106-inch span and 6000 pounds rated capacity formed of the same metal and embodying the novel cross-sectional configuration of the present invention had the following characteristics:

Span: 106 inches.
20 Rated capacity per pair: 6000 lbs.
Section: 4 $\frac{1}{2}$ inches (height) x 2 inches (width) x No. 7 gauge.
25 Blank size: 8 $\frac{1}{16}$ inches x 106 inches x No. 7 gauge.
Weight per beam: 45.9 lbs.
Twist at rated load: 2°.
30 Deflection at rated load: 0.330 inch.

Thus, each conventional beam member weighed 11 pounds more than one constructed according to the invention, required $\frac{1}{2}$ inch more clearance, twisted 4.5° more at rated load, and deflected only 0.029 inch less at rated load.

In FIGS. 8A and 8B there are set forth tabulations of test results which facilitate a further comparison of conventional channel section beams with beams embodying the present invention. Each of the beams listed in FIGURES 8A and 8B was manufactured from hot rolled, commercial quality, U.S. standard gauge mild steel having an AISI designation of C-1017. For example, a pair of beams each 108 inches in length and formed of 7-gauge steel with the above-mentioned specifications so as to have a conventional channel section illustrated in FIG. 8A with a height (A) of 4 $\frac{1}{2}$ inches, and a width (B) of 2 $\frac{1}{2}$ inches were found to have a yield point per pair of 6,600 pounds and each beam weighed 5.470 pounds per foot. A pair of beams 108 inches long formed of 7-gauge steel with the same above-mentioned specifications so as to have a cross-sectional configuration embodying the present invention and a height (A) of 3 $\frac{1}{16}$ inches and a width (B) of 1 $\frac{3}{4}$ inches were found to have a yield point of 6,600 pounds per pair and each beam weighed 4.258 pounds per foot. Thus, the beams embodying the present invention had the same capacity as the conventional channel section beams, but the height of the beams of the present invention was 1 $\frac{1}{16}$ inches less than that of the conventional beams and the beams embodying the present invention weighed 1.212 pounds per foot less than the conventional channel section beams. Thus, a nine-foot beam embodying the present invention weighed 10.908 pounds less than the conventional beam. Assuming, for example, that each section of the rack illustrated in FIGURE 1 had three shelves, six beams would be required and the beams embodying the present invention require 65.448 pounds less steel per section of three shelves than the conventional beams having the same capacity. Other comparisons as to the advantages of the present invention may be readily made by referring to FIGS. 8A and 8B.

It will thus be seen that using the same stock blank size, beams with greater capacities can be constructed when

following the principles of the invention, and for a specified capacity, less metal will be required, thus reducing both manufacturing and shipping costs. The decrease in required beam height will increase the total available storage space in each rack section, and, in some installations, this would permit the addition of another level in each section, thereby increasing the total volume available for storage, or in the alternative permit a reduction in the total number of sections and the floor space required. The recess defined by the web portions 25, 26, 27 provided when beam 13 is constructed as shown in FIGURE 7, also affords a protected area for labels for identifying the rack openings and the material stored therein.

While a preferred embodiment of the invention has been shown and described, it will be appreciated that various changes and modifications may be made without departing from the spirit of the invention.

I claim:

1. A beam comprising first and second spaced parallel flanges, the outer surface of at least one of said flanges having two laterally spaced coplanar areas near the flange edges simultaneously engageable by a load extending across said beam, a web comprising a central web portion perpendicular to and between said flanges and spaced therefrom, said central web portion being spaced a substantial lateral distance from both pairs of corresponding flange edges, a first inclined web portion connecting one edge of said central web portion with one edge of said first flange, and a second inclined web portion connecting the other edge of said central web portion with one edge of said second flange.

2. A beam comprising first and second spaced parallel flat flanges, a web comprising a central web portion perpendicular to and between said flanges and spaced therefrom, said central web portion being spaced a substantial lateral distance from both pairs of corresponding flange edges, a first inclined web portion connecting one edge of said central web portion with one edge of said first flange, and a second inclined web portion connecting the other edge of said central web portion with one edge of said second flange.

3. A beam comprising first and second spaced parallel flanges, the outer surface of at least one of said flanges having two laterally spaced coplanar areas near the flange edges simultaneously engageable by a load extending across said beam, a web comprising a central web portion perpendicular to and between said flanges and spaced therefrom, said central web portion being spaced a substantial lateral distance from both pairs of corresponding flange edges, a first inclined web portion connecting one edge of said central web portion with one edge of said first flange, and a second inclined web portion connecting the other edge of said central web portion with the corresponding edge of said second flange.

4. A beam comprising first and second spaced parallel flat flanges, a web comprising a central web portion perpendicular to and between said flanges and spaced therefrom, said central web portion being spaced a substantial lateral distance from both pairs of corresponding flange edges, a first inclined web portion connecting one edge of said central web portion with one edge of said first flange, and a second inclined web portion connecting the other edge of said central web portion with the corresponding edge of said second flange.

5. A beam comprising first and second spaced parallel flat flanges a web comprising a central web portion perpendicular to and between said flanges and spaced therefrom, said central web portion being spaced a substantial lateral distance from both pairs of corresponding flange edges, a first inclined web portion connecting one edge of said central web portion with one edge of said first flange, and a second inclined web portion connecting the other edge of said central web portion with one edge of said second flange, said central web portion being laterally spaced from one of said pairs of corresponding flange

edges approximately 40% to 65% of the distance between said pairs of corresponding flange edges, the width of said central web portion being approximately 20% to 60% of the total size of said beam cross section between the outer surfaces of said flanges.

6. A beam comprising first and second spaced parallel flat flanges, a web comprising a central web portion perpendicular to and between said flanges and spaced therefrom, said central web portion being spaced a substantial lateral distance from both pairs of corresponding flange edges, a first inclined web portion connecting one edge of said central web portion with one edge of said first flange, and a second inclined web portion connecting the other edge of said central web portion with one edge of said second flange, the distance between the opposite pairs of corresponding flange edges being approximately 25% to 65% of the total size of said beam cross section between the outer surfaces of said flanges.

7. A beam formed from initially flat metal stock comprising first and second spaced parallel flat flanges, a web comprising a central web portion perpendicular to and between said flanges and spaced therefrom, said central web portion being spaced a substantial lateral distance from both pairs of corresponding flange edges, a first inclined web portion connecting one edge of said central web portion with one edge of said first flange, and a second inclined web portion connecting the other edge of said central web portion with the corresponding edge of said second flange.

8. A beam formed from initially flat metal stock comprising first and second spaced parallel flat flanges, a web comprising a central web portion perpendicular to and between said flanges and spaced therefrom, said central web portion being spaced a substantial lateral distance from both pairs of corresponding flange edges, a first inclined web portion connecting one edge of said central web portion with one edge of said first flange, and a second inclined web portion connecting the other edge of said central web portion with one edge of said second flange, the distance between the opposite pairs of corresponding flange edges being approximately 25% to 65% of the total size of said beam cross section between the outer surfaces of said flanges.

9. A beam formed from initially flat metal stock comprising first and second spaced parallel flat flanges, a web comprising a central web portion perpendicular to and between said flanges and spaced therefrom, said central web portion being spaced a substantial lateral distance from both pairs of corresponding flange edges, a first inclined web portion connecting one edge of said central web portion with one edge of said first flange, and a second inclined web portion connecting the other edge of said central web portion with the corresponding edge of said second flange, the distance between the opposite pairs of corresponding flange edges being approximately 25% to 65% of the total size of said beam cross section between the outer surfaces of said flanges, the width of said central web portion being approximately 20% to 60% of the total size of said beam cross section between the outer surfaces of said flanges.

10. A beam member for use in conjunction with an adjustable storage rack comprising a beam and connecting members secured to the opposite ends of said beam, said beam having upper and lower flat horizontal flanges, a web comprising a vertical web portion between said

flanges and spaced therefrom, said vertical web portion being spaced a substantial horizontal distance from both pairs of corresponding flange edges, a first inclined web portion connecting the upper edge of said vertical web portion with one edge of said upper flange, and a second inclined web portion connecting the lower edge of said vertical web portion with the corresponding edge of said lower flange.

11. A rack construction comprising a plurality of end units each having front and rear posts and cross members

connecting said posts to form a rigid unit, front and rear beam members connecting front and rear posts, respectively, of adjacent end units, each beam member comprising a beam having connecting members at opposite ends thereof adapted to be removably mounted on said front or rear posts, each beam having upper and lower flat horizontal flanges, a web comprising a vertical web portion between said flanges and spaced therefrom, said vertical web portion being spaced a substantial horizontal distance from both pairs of corresponding flange edges, 10 a first inclined web portion connecting the upper edge of said vertical web portion with one edge of said upper flange, and a second inclined web portion connecting the lower edge of said vertical web portion with the corresponding edge of said lower flange.
